To all whom it may concern:

Be it known that I, H. W. Hensel, of the City and County of Philadelphia, State of Pennsylvania, have invented or produced a new and original design for a Blind Binding; and I do hereby declare the accompanying drawing with the following explanation of the same to form a full, clear and exact description of the said design.

The drawing represents sufficient of a strip of blind binding to illustrate my new design.

A and B, are two roses, and from a cluster of leaves C, above the rose A, projects a stem bearing a partly opened bud D. Beneath the rose B, is a cluster of leaves C', from which hangs a stem bearing a bud D'.

I claim the ornamental figures and forms represented in and by the accompanying drawing, in respect
